CIRCULAR KNITTING MACHINE

John Cyril Herbert Hurd, Leicester, England, assignor to Wildt and Company Limited, Leicester, England, a British company

Application May 10, 1940, Serial No. 334,445
In Great Britain May 16, 1939

13 Claims.

(Cl. 66—14)

This invention relates to circular knitting machines, and has particular reference to circular knitting machines of the double axially opposed needle cylinder type.

The invention is intended for application principally to machines of the kind having superimposed rotary needle cylinders furnished with double-ended needles operable by means of sliders as exemplified in the specifications of United Kingdom of Great Britain Letters Patents Nos. 24,290 of 1912 and 391,212.

Further, the invention is applicable to machines of the aforesaid characteristic type having two or more feeders and provision for automatically effecting changes such, for example, as are required for producing plain fabric, welts, rib fabric, purl fabric, fancy rib and purl effects or/and different combinations of rib, patterned fabric such as may be produced by means of yarns of different colours or/and selective operation of the needles, and jacquard purl effects.

The present invention is concerned with changes customarily effected by automatically operating, e. g. withdrawing from or putting into action or adjusting machine cams for operating the needles, or their associated sliders in a machine having double-ended needles.

The invention, moreover, concerns principally the operation of the welt cams of the machine although it may be extended to the operation of other machine cams, such for example as transfer cams and stitch cams, especially stitch cams conjointly with the welt cams.

The present invention, then, comprises a simple arrangement of mechanism for operating the machine cams as will be hereinafter described.

A practical arrangement constituting one example of the invention as applied to a circular knitting machine of the superimposed rotary needle cylinder type will presently be described.

In the accompanying drawings,

Figure 1 is a general perspective view, drawn diagrammatically, of so much of the machine as is necessary to illustrate the application thereto of the said invention.

Figures 2 and 2a together constitute a plan view of the relevant parts of the machine.

Figure 3 is a detail plan view illustrating a modification hereinafter to be described.

Figure 4 is an elevational view of intermediate connections employed in the operation of stitch cams conjointly with a welt cam.

Figure 5 is a developed lay-out of a portion of the cam system of the machine—at two adjacent feeds—purporting to show some of the machine

cams which are operated by the improved mechanism, and

Figure 5a is a view similar to Figure 5 showing the remainder of the cam system.

Like parts are designated by similar reference characters throughout the drawings.

Now the invention includes an arrangement of operating cams, for any particular set of two or more machine cams, in one plane, and an arrangement of cam pieces or like elements on a control drum, ring or like body suchwise that just prior to the commencement of a cycle of operations of the said set of the machine cams the corresponding cam pieces or like elements are respectively at different angular distances, equivalent to different numbers of racks of the drum, ring or like body, from the points of operation of the machine cams. Thus with the first cam piece or like element the distance of one rack from the point of operation of the corresponding machine cam or cams, the next cam piece or like element would be two racks from the point of operation of the next machine cam or cams in the same set and so on according to the number of points of operation and cam pieces or like elements provided. For example, in the case of a four feeder machine having a set of four welt cams or transfer cams the fourth cam piece or like element under the conditions aforesaid would be four racks away from the point of operation of the fourth machine cam while the first cam piece or like element would be but one rack away from the point of operation of the first machine cam.

As will be understood, by a "rack" is meant the angular distance through which the control drum, ring or like body is turned or racked by the action of an operating cam in the intermediate connections. There may be in the same series of operating cams in one plane different operating cams for different sets of machine cams, and accordingly there may be different sets of cam pieces or like elements arranged as aforesaid on the control drum or like body. Alternatively, there may be different sets of operating cams and different sets of cam pieces or like elements arranged in the way described for different sets of machine cams.

In Figure 1 of the drawings superimposed rotary plain or bottom and rib or top needle cylinders are indicated at 1 and 2 respectively. The bottom cam box, which is secured to the bottom plate 3 of the machine, is represented at 4, while the top cam box, shown at 5, depends from and is attached to the underside of the customary top

plate 6, all in accordance with conventional design.

According to the arrangement illustrated operating cams, such as those shown at 7, 8, 9, 10, 11 and 12 (see Figure 2) are mounted circumferentially and at the same level on the cylinder driving gear (not shown) or otherwise associated with the bottom needle cylinder 1 and cam pieces or like elements such as those represented at 13, 14, 15, 16, 17 and 18 are mounted in a control unit in the form of a grooved ring 19 mounted on the aforesaid top plate 6. The operating cams, which are therefore all in one plane beneath the bottom plate 3, may conveniently be secured within a circumferential groove in a hub or like integral part of the conventional bevel driving gear. In association with this cam arrangement there is provided a lever 20 fitted with a cam roller 21 for contact with the operating cams at desired times. This lever is mounted on a vertical rack shaft 22 to which is attached the pawl lever 23 of a pawl and ratchet mechanism for racking the control ring 19.

The lever 20, moreover, is held normally inoperative, that is to say in the position shown in Figures 1 and 2, until required changes are to be effected by means of a catch 24 adapted to be operated, to release the lever, from the existing timing or controlling mechanism of the machine, or from an auxiliary unit such as a separate timing chain. In the specific example depicted in Figures 1 and 2, the catch 24 consists of a pivoted lever which is mounted beneath the bottom plate 3 and formed with a protuberant claw-like formation 24a adapted for engagement at appropriate times with a pin or projection 25 provided on the lever 20. In Figure 1 one of the cam bits on a timing chain is designated at 26, and the chain itself is racked round in the usual way by pawl and ratchet mechanism 27, 28, the pawl of which is operated by a reciprocating rod 29 fitted with a cam roller 30 for contact with a cam or cams (not shown) arranged to revolve about an axis concentric with the axis of the needle cylinders. The cam bits on the chain are arranged for action on one arm of a two-armed pivoted lever 31, and intermediate connections such, for instance, as the link 32, the bell crank 33 and the curved link 34, are provided between said lever and the catch 24. As will be understood the catch is arranged so as to engage the lever 20 when the latter is moved outwards by the operating cams. Release of the lever 20 is, of course, obtained by turning the catch 24 in an anti-clockwise direction, and such a movement is effected each time a cam bit 26 engages the toe 31a of the lever 31. Preferably, the connections between the catch 24 and the lever 31 are spring loaded or controlled. Conveniently for this purpose, a tension spring such as 35 may be anchored at one end to an appropriate portion of the bell crank 33 and at its other end to a pin or peg on the bottom plate 3.

The rack shaft 22 is mounted to turn in suitable bearings in the top and bottom plates of the machine, and the pawl lever 23 is rigidly attached to the extreme upper end of said shaft which end projects somewhat above the top plate 6. A spring-controlled pawl 36 is pivotally mounted at the outer end of the pawl lever 23 and adapted for co-operation with ratchet teeth 37 formed around the periphery of the control ring 19. The lever 20, the vertical rack shaft

22 and the pawl lever 23 all turn together, and these parts are spring-controlled. For this latter purpose there may conveniently be provided a tension spring such as that depicted at 38 in Figure 1, one end of this spring being anchored to a convenient part of the lever 20 while the opposite end thereof is anchored to a pin or projection 39 secured in the bottom plate 3. Now, assuming the machine to be in operation and the catch 24 to have been actuated suchwise as to effect release of the lever 20, then each time one of the operating cams 7-12 engages the roller 21 the lever 20 will be moved outwards with the result that the rack shaft 22 together with the pawl lever 23, will be turned in an anti-clockwise direction—against the action of the spring 38—thereby imparting an operative stroke to the pawl 36. Immediately an operating cam passes the roller 21, however, the lever 20 will be pulled inwards under the influence of the spring 38 so that the pawl lever 23 is caused to make a reverse, i. e., idle, stroke. Each time a complete operative stroke is imparted to the pawl 36, the control ring 19 will be turned or racked in the direction of the arrow A to the extent of one step. In Figure 2 the angular distance constituting one rack is indicated at a. If, as shown, there are six operating cams in one plane, then the control ring 19 will be racked six times at each revolution of the machine. Thus, the total angular distance through which said ring is turned at each such revolution is $a \times 6$, i. e. a distance b.

The control ring 19 is formed with a plurality of concentric annular grooves 19a in which the cam pieces or like elements, appropriately arranged, are secured by means of screws 40. For the sake of clarity in Figure 2 only six cam pieces are shown, these particular cam pieces being employed during a cycle of operations to effect a change from the production of a welt to 2/2 rib knitting by operation of the bottom welt cams and top transfer cams in the manner presently to be described. It is to be understood, however, that in actual practice the control ring would be furnished with several other cam pieces or like elements and that these would be appropriately prearranged so as to enable various other changes, such as those mentioned hereinafter, to be effected during the production of a garment length or article.

The machine cams to be controlled from the control ring 19 are represented in Figures 5 and 5a and will now be described. The particular machine with which the present description is concerned has four feeders and accordingly the bottom and top cam boxes 4 and 5 are each made up of four sections. Thus the first and second sections S¹ and S² of the bottom cam box are shown in Figure 5, while the third and fourth sections S³ and S⁴ of said box are shown in Figure 5a. Similarly, the first and second sections S^a and S^b of the top cam box are shown in Figure 5, and the third and fourth sections S^c and S^d of said top box are represented in Figure 5a. The sections S¹ and S^a together constitute the first feeder of the machine; the sections S² and S^b constitute the second feeder; the sections S³ and S^c together form the third feeder, and the remaining two sections constitute the fourth feeder. It will be noted that the third section in each box is identical with the first section in said box, and similarly the fourth section is identical with the second. Now, as will be seen, the first section S¹ of the bottom cam box 4

includes an adjustable plain stitch cam 41, a bottom welt cam 42 which is adapted to control the admission of appropriate slider butts to a welt track 43, and a bottom transfer cam 44. The third section S³ of this box similarly includes a stitch cam 41¹, a welt cam 42¹, a welt track 43¹ and a transfer cam 44¹. The second section S² of the bottom cam box includes an adjustable plain stitch cam 45, and the fourth section S⁴ includes a similar stitch cam 45¹. The first section S^a of the top cam box 5 includes an adjustable rib stitch cam 46, and a top transfer cam 47, whereas the third section S^c of this box similarly includes a rib stitch cam 46¹ and a transfer cam 47¹. The second section S^b of said top box includes an adjustable rib stitch cam 48, a top welt cam 49 adapted to control the admission of appropriate slider butts to a welt track 50, and two top transfer cams 51 and 52. Finally, the fourth section S^d includes a stitch cam 40¹, a welt cam 49¹, a welt track 50¹ and two transfer cams 51¹ and 52¹. The various adjustable stitch cams are each mounted on a slide 53 (see Figure 4). The welt and transfer cams are all of the bolt type movable radially in their cam boxes and spring controlled. These bolt cams, moreover, are normally held withdrawn against the spring action and when released spring into their operative positions.

The intermediate mechanisms constituting the points of operation of the machine cams may be of any suitable form. Advantageously, operation of a welt cam is effected conjointly with quality adjustment of adjacent stitch cams at the same feeder for producing slack courses in the welts, for which purpose such welt cam and stitch cams may be operated from the control ring 19 through intermediate mechanism common to both or through independent intermediate mechanisms. One form of mechanism through which rib and plain stitch cams 46 (46¹) and 41 (41¹) respectively and a bottom welt cam 42 (42¹) are operated conjointly will now be described, by way of example, with reference to Figures 2 and 4. As will be seen, then, a lever 54 which is pivoted at 55 on the top cam box 5 has a pin-and-slot connection 56, 57 with the slide 53 of the rib stitch cam 46 (46¹). The position normally occupied by this rib stitch cam is determined by an adjustable stop 58 which is in the form of a screw arranged for contact with a part of or on the slide 53. The stop 58 is carried by a part 59 attached to the cam box 5. The lever 54 is controlled by a tension spring 60 arranged as shown. Adjustment of the cam 46 (46¹) is therefore effected by turning the lever 54 upwardly on its pivot to raise the associated slide 53 to the required extent against the spring action. The extent of this movement can be varied by suitable adjustment of the screw 58, and for facilitating this adjustment there is provided a pivoted pointer 61 which latter is connected to the rib stitch cam slide and movable in relation to a fixed scale 62 appropriately graduated or calibrated. The lever 54 is actuated by a rod 63 which extends upwardly through the top plate 6 and is connected at 64 to an arm 65. The plain stitch cam 41 (41¹) at the same feeder is adapted to be adjusted simultaneously with adjustment of the last mentioned rib stitch cam through the medium of a link 66 and a lever 67. The said lever is arranged to pivot at 68 on the bottom cam box 4 and at the end remote from the link 66 makes contact with an adjustable screw 69 carried by the plain stitch

cam slide. The position normally occupied by the plain stitch cam is determined in the usual way by an adjustable stop 70. A pivoted pointer 71 connected to the plain stitch cam slide is provided in association with an appropriately graduated or calibrated scale 72. The arrangement is therefore such that whenever the arm 65 and hence also the operating rod 63, is lifted, the rib stitch cam will be raised and the plain stitch cam correspondingly depressed, and vice versa, to vary the quality of the stitch; the arm 65 is appropriately bossed and mounted to turn on a horizontal spindle 73 which latter is carried in brackets 74 and 75 secured to the top plate 6. The outer end of the arm 65 carries a screw 76 the leading end of which is arranged in the path of a cam piece secured within an appropriate groove 19a in the control ring 19; this cam piece is not shown. The bottom welt cam 42 (42¹) located adjacent to the plain stitch cam 41 (41¹) is operated by a rod 77 which extends upwardly through the top plate 6 and is connected to an arm 78. This arm is independently mounted on the spindle 73 and rigidly connected by means of an integral bridge portion 79 to another arm 80. The arm 80, which is also bossed and mounted on the spindle 73, is furnished with a toe-piece 81 (81¹) arranged in the path of another of the cam pieces on the grooved control ring. The rod 77 is loaded, e. g., by means of a tension spring such as 82 arranged as shown in Figure 4. At its lower end the rod 77 is connected to a rotary element 83 which has cam formations adapted to act upon a transverse pin 84 secured in the bolt 85 of the bottom welt cam to be operated. Whenever the toe-piece 81 (81¹) is lifted by a cam piece, the rod 77 is raised against the action of the spring 82 to effect withdrawal of the welt cam 42 (42¹) thereby admitting appropriate slider butts to the welt track 43 (43¹). Conversely, whenever the said toe-piece is permitted to drop off a cam piece under the spring action the welt cam will move in and close the track 43 (43¹). From a consideration of Figure 2 it will be appreciated that the bottom welt cam 42 at the first section S¹ of the bottom cam box is operated from the cam piece 13, whereas the corresponding welt cam 42¹ at the third section S³ of said box is operated from the cam piece 16.

Now, whenever a welt cam is operated the adjacent stitch cams are adjusted conjointly in the appropriate manner. But as will be seen from Figures 5 and 5a, in each instance a welt cam is spaced apart circumferentially to a small extent from the corresponding stitch cam. Accordingly, it is necessary to effect adjustment of such stitch cams slightly in advance of the time at which the welt cam is operated. Thus, for instance, just prior to moving in the bottom welt cam 42 (42¹), it is necessary to raise the plain stitch cam 41 (41¹) and simultaneously depress the rib stitch cam 46 (46¹). To achieve this result the cam pieces concerned are appropriately arranged upon the control ring 19 and the latter—instead of being racked round one complete step—is turned two half racks by the action of a single operating cam upon the cam roller 21, suchwise as to permit the screw 76 to drop off its cam piece a little earlier than the toe-piece 81 (81¹). In this connection the reader's attention is directed to the operating cams 7, 8, 10 and 11 (Figure 2) each of which is stepped for the purpose just mentioned.

Other intermediate mechanisms are also shown

in Figure 2. For instance, the top welt cams 49 and 49¹ are operated by rods 86 attached to arms 87 which are rigidly secured to spindles 88. Arms 89 similarly secured to said spindles carry toe-pieces 90 and 90¹ for co-operation with appropriately arranged cam pieces on the control ring 19. The stitch cams 45 and 45¹ and 48 and 48¹ to be adjusted conjointly with operation of the top welt cams 49 and 49¹ are actuated from rods 91. These rods are attached to arms 92 which are suitably bossed and mounted on the spindles 88 independently of the arms 87. As will be appreciated the arms 92 are similar in design and function to the arms 65 aforesaid. With regard to the top and bottom transfer cams these are conveniently operated by rods 93 attached to arms such as 94 which are fixed upon spindles 95. These spindles are adapted to be rocked at appropriate times to actuate the rods 93 by the action of cam pieces upon toe-pieces such as 96 and 96¹ carried by arms 97 which are also rigidly secured to the spindles 95.

As previously mentioned, for the sake of clarity only six cam pieces are represented in Figure 2. In accordance with the present invention these cam pieces are arranged on the control ring 19 suchwise that just prior to a change from the production of a welt to 2/2 rib knitting, it will require one rack *a* of said ring to enable the toe-piece 81 to drop off the cam piece 13 at the point 13a; two complete racks of the ring 19 to enable the toe-piece 96 to drop off the cam piece 14 at the point 14a; three racks of the ring before the toe-piece 90 drops off the cam piece 15 at the point 15a; four racks of the control ring before the toe-piece 81¹ drops off the appropriate end 16a of the cam piece 16; five racks of the ring to enable the toe-piece 96¹ to drop off the end 17a of the cam piece 17; and six complete racks (a distance *b*) before the toe-piece 90¹ drops off the end 18a of the cam piece 18.

By way of example the precise movements which take place during the change last referred to will now be set forth. Assume that the series of operating cams 7—12 are rotating in the direction of the arrow A in Figure 1 and that the control ring 19 is adapted to be racked round in the same direction. As will be seen the cam 7 is approaching the cam roller 21. When said cam acts on this roller the rack shaft 22 will be turned twice in an anti-clockwise direction, with the result that two movements will be imparted to the control ring 19—each movement being to the extent of half a complete rack. At the first half rack the screw 76 (shown at the bottom of Figure 2) will drop off a cam-piece thereby effecting simultaneous adjustment of the stitch cams 41 and 48; at the second half rack the toe-piece 81 will drop off the cam piece 13, with the result that the bottom welt cam 42 will move in to close the welt track 43. Next, the cam 12 acts on the roller 21 to impart one complete rack to the ring 19, and as a result of this second rack the toe-piece 96 drops off the cam piece 14 and the 2/2 top transfer cam 51 moves in. A third rack (in two separate movements) is then imparted to the ring 19 by reason of the cam 11 passing in contact with the cam roller 21. At the first half of this third rack the appropriate arm 92 is permitted to drop so that the stitch cams 45 and 48 are adjusted. At the second half of said third rack the toe-piece 90 drops off the cam piece 15 whereby the top welt cam 49 is allowed to move in to close the welt track 50. By reason of the cam 10 next acting on the

roller 21, the ring 19 is once again racked round (the fourth rack) in two separate movements; at the first of these movements the screw 76 (shown at the top of Figure 2) will drop off a cam piece to effect adjustment of the stitch cams 41¹ and 46¹, whereas at the second movement the toe-piece 81¹ will drop off the cam piece 16 suchwise as to enable the bottom welt cam 42¹ to move in to close the welt track 43¹. The fifth rack of the control ring is obtained when the cam 9 engages the roller 21 at which time the toe-piece 96¹ will drop off the cam piece 17 to move in the 2/2 top transfer cam 51¹. Lastly, the cam 8 will, by action on the cam roller 21, effect a sixth rack of the ring 19 in two stages. At the first stage the appropriate arm 92 will be permitted to drop suchwise as to effect simultaneous adjustment of the stitch cams 45¹ and 48¹, whereas at the second stage the toe-piece 90¹ will drop off the cam piece 18 to allow the top welt cam 49¹ to move in, thereby closing the welt track 50¹.

In elaboration of what has already been described, it is considered desirable to make the following observations:

The machine illustrated may conveniently be constructed to make a French welt prior to which several courses of ordinary purl fabric may be made by causing all the needles to knit in the top cylinder at one feeder and all the needles to knit in the bottom cylinder at the next or adjacent feeder, and so on.

If, as may be, the machine is furnished with mechanism for inserting a draw thread, then it is at the last of the purl courses at a feeder where all the needles are knitting in the top cylinder that the draw thread is actually inserted. The operation of the welt cams, stitch cams and 2/2 transfer cams is performed seriatim on a definite slider, i. e. a change slider, in each of the top and bottom cylinders, when the particular slider is in line with the corresponding welt cam. This change slider is the first slider to pass along the appropriate welt track. In setting up the machine the top change slider is inserted one trick in advance of the bottom change slider.

At the next, i. e. first, feeder, when all the needles are in the bottom cylinder, the welt proper is commenced by first effecting adjustment of the stitch cams 41 and 46 and then withdrawing the welt cam 42 at that feeder.

This welt cam operates on the knitting butts of sliders which are set out with a long butt alternating with a short butt, and when the welt cam is withdrawn it allows sliders having short butts to pass along the welt track 43 and sliders with long butts to clear in the usual manner. As the bottom transfer cam 44 is in, all those long butt sliders which cleared transfer their corresponding needles to the top cylinder and in this manner a 1/1 rib formation is produced from a plain knitted course. At the second feeder, the stitch cams 45 and 48 are adjusted and the top welt cam 49 is withdrawn. This top welt cam, similarly to the bottom welt cam 42, operates on the knitting butts of the sliders, which are set out with a long butt alternating with a short butt. The short butt sliders pass along the welt track 50 and as these are carrying the needles transferred up at the previous feeder, there is a cessation of knitting at this feeder in the top cylinder. The sliders furnished with long knitting butts in the top cylinder are not engaged with needles at this stage.

In the bottom cylinder at the second feeder, all sliders clear so that those engaged with a needle

cause said needle to knit; that is to say, at this feeder needles which alternate with those in the top cylinder knit.

At the third and fourth feeders, similar action takes place to that described with respect to the first and second feeders.

The change from welt to 2/2 rib is effected immediately after a complete welt is made, that is to say, after the machine has made one complete revolution from the commencement of the welt, 10 and the bottom change slider is once again in alignment with the welt cam 42.

At this stage the welt cam 42 moves in, and, following the change sliders round the machine, the 2/2 transfer cam 51 moves in.

The transfer butts of the top sliders are set out with two long butts alternating with two short butts, and the first two long butts down must be at least one slider behind the bottom change slider.

When the change slider is in alignment with the welt cam 49 said cam moves in and, as the cylinders revolve, welt cam 42¹ then the other 2/2 transfer cam 51¹ and finally the welt cam 49¹ all move in sequentially so that the machine is then making 2/2 rib fabric. Normally this latter is made at the same quality or stitch length as the welt.

To effect a change from 2/2 rib to reverse knitting

First, both the bottom and top 2/2 transfer cams following the first feeder and the customary selector unit are simultaneously withdrawn when the 2/2 change sliders are in alignment with the 2/2 top transfer cam 51. Following the machine round, the stitch cams 45 and 48 are operated at the second feeder, then the stitch cams 41¹ and 46¹ are operated at the third feeder, the bottom and top 2/2 transfer cams after the third feeder are withdrawn simultaneously, the stitch cams 45¹ and 48¹ at the fourth feeder are operated and finally the stitch cams 41 and 46 at the first feeder are operated.

Assume now that the control ring 19 has seventy-two teeth and is turned to the extent of six racks at each revolution of the machine. Then if, as may be, the machine is set out so that two complete garment lengths can be produced while the control ring 19 is turned through one revolution, there will be thirty-six racks for each garment, giving a possibility of six changes per garment. Each series of six racks is controlled from the timing chain 26 so that for controlling the movements of the ring 19 there need only be six cam bits on said chain, these cam bits being arranged in two groups of three.

The following is one example of a series of complete changes which can be obtained with an appropriate layout of cam pieces on the control ring and a suitable arrangement of intermediate connections under the circumstances specified in the last preceding paragraph:

Racks 1-6

During these racks a change is made from the production of patterned to purl knitted fabric, and the transfer cams 44, 52, 44¹ and 52¹ are moved in simultaneously at the 1st rack.

Racks 7-12

These racks effect a change from purl to welt, but just prior to the knitting of the welt a draw-thread is inserted at the last of the feeders at which the purl fabric is knitted. At the 7th rack the stitch cams 41 and 46 are operated and the

welt cam 42 is withdrawn. The 8th rack is an idle one. At the 9th rack the stitch cams 45 and 48 are operated and the welt cam 49 is withdrawn. The 10th rack results in operation of the stitch cams 41¹ and 46¹ and withdrawal of the welt cam 42¹. The 11th rack is an idle one, and at the 12th rack the stitch cams 45¹ and 48¹ are operated and the welt cam 49¹ is withdrawn.

Racks 13-18

During these racks a change is made from the welt to 2/2 rib knitting. This sequence of operations has previously been given in detail, but it is repeated again, briefly, for the sake of continuity. The 13th rack permits of appropriate adjustment of the stitch cams 41 and 46 and allows the welt cam 42 to move in. (Also, the transfer cams 52 and 52¹ are withdrawn at this rack.) The transfer cam 51 moves in at the 14th rack. At the 15th rack the stitch cams 45 and 48 are adjusted and the welt cam 49 moves in. The 16th rack permits of appropriate adjustment of the stitch cams 41¹ and 46¹ and allows the welt cam 42¹ to move in. At the 17th rack the transfer cam 51¹ moves in, and at the 18th rack the stitch cams 45¹ and 48¹ are adjusted and the welt cam 49¹ moves in.

Racks 19-24

These six racks change the machine from 2/2 rib to the production of patterned work. The 19th rack is an idle one. The 20th rack effects withdrawal of the transfer cams 44 and 51. At the 21st rack the stitch cams 45 and 48 are operated. The 22nd rack effects operation of the stitch cams 41¹ and 46¹. At the 23rd rack the transfer cams 44¹ and 51¹ are withdrawn, and the 24th rack effects operation of the stitch cams 45¹ and 48¹.

Racks 25-30

The 25th rack effects operation of the stitch cams 41 and 46, and the remaining five of these six racks are idle.

All of racks 31-36 are idle ones.

Racks 37-72

As will be readily appreciated this second group of thirty-six racks effects precisely the same changes as those effected during racks 1-36.

Instead of employing the catch 24 for the purpose of holding the lever 20 inoperative until required changes are to be effected, as hereinbefore explained, the form of catch mechanism depicted in Figure 3 may, alternatively, be adopted. This mechanism includes a catch or trip lever 98 formed with a claw-like formation 98a adapted for engagement at appropriate times with the pin or projection 25. This lever is pivoted at 99 and, in a somewhat similar way to the catch 24, is operable to release the rack lever 20 from the aforesaid timing or controlling mechanism—through the medium of intermediate connections including the curved link 34. Upon release, the rack lever 20 springs into the path of the operating cams, one of which latter is indicated at 100. Mounted upon the catch or trip lever 98 is a slide 101 which is formed with a jaw 101a. The slide is suitably guided and retained in position by plates 102 and 103. A tension spring 104, arranged as shown, serves to control said slide. The catch or trip lever 98 is controlled by a spring 105. Now at such times as the rack lever 20 is not required to operate, it is held inoperative, i. e. in the position shown, with the pin or projection 25 trapped between

the claw 98a and the jaw 101a. Whenever the said catch or trip lever is operated to release the rack lever 20, however, the slide 101 springs forward into the path of a catch-tripping cam or cams—one of which is represented by way of example at 106. The idea of providing the slide 101 in conjunction with the tripping cam or cams is to prevent premature re-engagement of the catch or trip lever 98 (after release) with the rack lever 20. As will be seen, the leading end of the tripping cam 106 is in advance of the operating cam 109. When said tripping cam engages the end of the slide 101 it swings the latter, and hence also the lever 98, in an anti-clockwise direction clear of the pin or projection 25 so that the parts take up the positions indicated in dot-and-dash lines. The parts are held in this position for a length of time depending on the circumferential extent of the cam 106, and during this time the rack lever 20 is, of course, permitted to function for a sequence of racks without being arrested. If no tripping cam is provided in advance of an operating cam, then the pin or projection 25 will come into contact with the slide 101 and force it against the spring action. As a consequence, the catch or trip lever 98 will be turned slightly in an anti-clockwise direction, thereby allowing the pin or projection 25 to ride past the claw 98a. By reason of it being spring-controlled the catch or trip lever 98 will then spring into its operative position to hold the rack lever inoperative. The tripping cam or cams is or are of the same circumferential disposition as the first operating cam or all but one of the operating cams, according as to whether there are two or more. The tripping cam or cams is or are, moreover, preferably made thinner, and is or are located underneath but at a somewhat lower level than the corresponding operating cam or cams. In this way when a cycle of operations of the machine cams has been initiated by release of the lever 20 the catch is prevented from engaging the said lever and holding it inoperative until the second or last of the operating cams has acted upon the lever, according to the number of operating cams provided, i. e. two or more in a machine having two or more feeders.

As will be appreciated, the expression "points of operation of the machine cams" used herein and in the appended claims is intended to include the points at which the cam pieces or like elements on the control drum or like body act upon opposing members of the intermediate mechanisms for operating the said cams.

What I claim then is:

1. In a circular knitting machine of the double axially opposed needle cylinder type, in combination, a plurality of machine cams, an arrangement of operating cams in one plane, said operating cams being driveable in timed relation with the rotational motion of the machine, a control unit from which said machine cams are controlled, means operable by the operating cams for racking round the control unit, an arrangement of cam pieces on said unit, and intermediate mechanisms between the control unit and the machine cams for operating the latter, the aforesaid arrangement of cam pieces being such that just prior to the commencement of a cycle of operations of the said machine cams the corresponding cam pieces are respectively at different angular distances, equivalent to different numbers of racks of said control unit, from the points of operation of the machine cams.

2. In a circular knitting machine of the double axially opposed needle cylinder type, in combination, respectively different sets of machine cams, a series of different operating cams in one plane for the different sets of machine cams, said operating cams being driveable in timed relation with the rotational motion of the machine, a control unit from which said machine cams are controlled, means operable by the operating cams for racking round the control unit, an arrangement of cam pieces on said unit, and intermediate mechanisms between the control unit and the machine cams for operating the latter, the aforesaid arrangement of cam pieces being such that just prior to the commencement of a cycle of operations of the said machine cams the corresponding cam pieces are respectively at different angular distances, equivalent to different numbers of racks of said control unit, from the points of operation of the machine cams.

3. In a circular knitting machine of the double axially opposed needle cylinder type, in combination, a plurality of machine cams, an arrangement of operating cams in one plane, said operating cams being driveable in timed relation with the rotational motion of the machine, a control unit from which said machine cams are controlled, timing mechanism, a lever movable into and out of operative relationship with the operating cams under the control of said timing mechanism, pawl and ratchet mechanism through the medium of which said lever operates to rack around the control unit, an arrangement of cam pieces on said unit, and intermediate mechanisms between the control unit and the machine cams for operating the latter, the aforesaid arrangement of cam pieces being such that just prior to the commencement of a cycle of operations of the said machine cams the corresponding cam pieces are respectively at different angular distances, equivalent to different numbers of racks of said control unit, from the points of operation of the machine cams.

4. In a circular knitting machine of the double axially opposed needle cylinder type, in combination, a plurality of machine cams, an arrangement of operating cams in one plane, said operating cams being driveable in timed relation with the rotational motion of the machine, a control unit from which said machine cams are controlled, timing mechanism, a lever movable into and out of operative relationship with the operating cams under the control of said timing mechanism, pawl and ratchet mechanism through the medium of which said lever operates to rack around the control unit, an arrangement of cam pieces on said unit, intermediate mechanisms between the control unit and the machine cams for operating the latter, the aforesaid arrangement of cam pieces being such that just prior to the commencement of a cycle of operations of the said machine cams the corresponding cam pieces are respectively at different angular distances, equivalent to different numbers of racks of said control unit, from the points of operation of the machine cams, and means for holding the aforesaid lever inoperative until required changes are to be effected, said last mentioned means being operable from the timing mechanism to release the lever at appropriate times.

5. A combination according to claim 4, wherein the said last mentioned means consists of a catch arranged so as to engage the lever when the latter is moved outwards by the operating cams.

6. In a circular knitting machine of the double

axially opposed needle cylinder type, in combination, a plurality of machine cams, an arrangement of operating cams in one plane, said operating cams being driveable in timed relation with the rotational motion of the machine, a control unit from which said machine cams are controlled, timing mechanism, a lever movable into and out of operative relationship with the operating cams under the control of said timing mechanism, pawl and ratchet mechanism through the medium of which said lever operates to rack round the control unit, an arrangement of cam pieces on said unit, intermediate mechanisms between the control unit and the machine cams for operating the latter, the aforesaid arrangement of cam pieces being such that just prior to the commencement of a cycle of operations of the said machine cams the corresponding cam pieces are respectively at different angular distances, equivalent to different numbers of racks of said control unit, from the points of operation of the machine cams, a catch arranged to engage the aforesaid lever when it is moved outwards by the operating cams for holding said lever inoperative until required changes are to be effected, said catch being operable from the timing mechanism to release the lever at appropriate times, and means in association with the catch to prevent premature re-engagement thereof with the lever after release.

7. In a circular knitting machine of the double axially opposed needle cylinder type, in combination, a plurality of machine cams, an arrangement of operating cams in one plane, said operating cams being driveable in timed relation with the rotational motion of the machine, a control unit from which said machine cams are controlled, timing mechanism, a lever movable into and out of operative relationship with the operating cams under the control of said timing mechanism, pawl and ratchet mechanism through the medium of which said lever operates to rack round the control unit, an arrangement of cam pieces on said unit, intermediate mechanisms between the control unit and the machine cams for operating the latter, the aforesaid arrangement of cam pieces being such that just prior to the commencement of a cycle of operations of the said machine cams the corresponding cam pieces are respectively at different angular distances, equivalent to different numbers of racks of said control unit, from the points of operation of the machine cams, a catch arranged to engage the aforesaid lever when it is moved outwards by the operating cams for holding said lever inoperative until required changes are to be effected, said catch being operable from the timing mechanism to release the lever at appropriate times, a movable part carried by the catch and at least one cam in a different plane from said operating cams for action upon the movable part to prevent premature re-engagement of the catch with the lever after release.

8. In a circular knitting machine, in combination, a rotary plain cylinder, a superimposed coaxial rotary rib cylinder, a top plate located above said rib cylinder, a plurality of machine cams, operating cams which are mounted circumferentially and at the same level suchwise as to be rotatable with the plain cylinder, a control unit mounted on the aforesaid top plate and from which said machine cams are controlled, means operable by the operating cams for racking round the control unit, an arrangement of cam pieces on said unit, and intermediate mech-

anisms between the control unit and the machine cams for operating the latter, the aforesaid arrangement of cam pieces being such that just prior to the commencement of a cycle of operations of the said machine cams the corresponding cam pieces are respectively at different angular distances, equivalent to different numbers of racks of said control unit, from the points at which the cam pieces act upon opposing portions of the intermediate mechanisms.

9. In a circular knitting machine, in combination, a rotary plain cylinder, a superimposed coaxial rotary rib cylinder, a top plate located above said rib cylinder, a plurality of machine cams, a series of operating cams which are mounted circumferentially at the same level and in such a manner as to be rotatable with the plain cylinder, a control unit from which said machine cams are controlled, said unit being in the form of a grooved ring and mounted on the top plate, timing mechanism, a lever movable into and out of operative relationship with the operating cams under the control of said timing mechanism, a shaft upon which said lever is mounted, pawl and ratchet mechanism through the medium of which the lever operates to rack round the control unit, said last mentioned mechanism including a pawl lever which is attached to said shaft, cam pieces arranged in the grooves of the control unit, and intermediate mechanisms between the control unit and the machine cams for operating the latter, the aforesaid arrangement of cam pieces being such that just prior to the commencement of a cycle of operations of the said machine cams the corresponding cam pieces are respectively at different angular distances, equivalent to different numbers of racks of said control unit, from the points of operation of the machine cams.

10. In a circular knitting machine of the double axially opposed needle cylinder type, in combination, a plurality of machine cams including welt cams and stitch cams, an arrangement of operating cams in one plane, said operating cams being driveable in timed relation with the rotational motion of the machine, a control unit from which said welt cams and stitch cams are controlled, means operable by the operating cams for racking round the control unit, an arrangement of cam pieces on said unit, and intermediate mechanisms between the control unit and the welt and stitch cams for operating said welt cams sequentially conjointly with operation of stitch cams, the aforesaid arrangement of cam pieces being such that just prior to the commencement of a cycle of operations of the said machine cams the corresponding cam pieces are respectively at different angular distances, equivalent to different numbers of racks of said control unit, from the points of operation of the machine cams.

11. In a circular knitting machine, in combination, a plain cylinder, a plain cam box associated with said cylinder, an axially opposed rib cylinder, a rib cam box associated with said rib cylinder, machine cams comprising welt cams, stitch cams and needle transfer cams in said cam boxes, an arrangement of operating cams in one plane, said operating cams being driveable in timed relation with the rotational motion of the machine, a control unit from which said welt cams, stitch cams and needle transfer cams are controlled, means operable by the operating cams for racking round the control unit, an arrangement of cam pieces on said unit, and

intermediate mechanisms between the control unit and the welt cams, stitch cams and transfer cams for operating said cams sequentially, the aforesaid arrangement of cam pieces being such that just prior to the commencement of a cycle of operations of the said machine cams the corresponding cam pieces are respectively at different angular distances, equivalent to different numbers of racks of said control unit, from the points of operation of the machine cams.

12. In a circular knitting machine, in combination, a rotary plain cylinder, a superimposed co-axial rotary rib cylinder, a top plate located above said rib cylinder, a plurality of machine cams, a series of operating cams which are mounted circumferentially at the same level and in such a manner as to be rotatable with the plain cylinder, a control unit from which said machine cams are controlled, said unit being in the form of a grooved ring and mounted on the top plate, timing mechanism, a lever movable into and out of operative relationship with the operating cams under the control of said timing mechanism, a shaft upon which said lever is mounted, pawl and ratchet mechanism through the medium of which the lever operates to rack round the control unit, said last mentioned mechanism including a pawl lever which is attached to said shaft, cam pieces arranged in the grooves of the control unit, intermediate mechanisms between the control unit and the machine cams for operating the latter, the aforesaid arrangement of cam pieces being such that just prior to the commencement of a cycle of operations of the said machine cams the corresponding cam pieces are respectively at different angular distances, equivalent to different numbers of racks of said control unit, from the points of operation of the machine cams, and means for holding the aforesaid lever inoperative until required changes are to be effected, said last mentioned means being operable from the timing

mechanism to release the lever at appropriate times.

13. In a circular knitting machine, in combination, a rotary plain cylinder, a superimposed co-axial rotary rib cylinder, a top plate located above said rib cylinder, a plurality of machine cams, a series of operating cams which are mounted circumferentially at the same level and in such a manner as to be rotatable with the plain cylinder, a control unit from which said machine cams are controlled, said unit being in the form of a grooved ring and mounted on the top plate, timing mechanism, a lever movable into and out of operative relationship with the operating cams under the control of said timing mechanism, a shaft upon which said lever is mounted, pawl and ratchet mechanism through the medium of which the lever operates to rack round the control unit, said last mentioned mechanism including a pawl lever which is attached to said shaft, cam pieces arranged in the grooves of the control unit, intermediate mechanisms between the control unit and the machine cams for operating the latter, the aforesaid arrangement of cam pieces being such that just prior to the commencement of a cycle of operations of the said machine cams the corresponding cam pieces are respectively at different angular distances, equivalent to different numbers of racks of said control unit, from the points of operation of the machine cams, a catch arranged to engage the aforesaid lever when it is moved outwards by the operating cams for holding said lever inoperative until required changes are to be effected, said catch being operable from the timing mechanism to release the lever at appropriate times, and means in association with the catch to prevent premature re-engagement thereof with the lever after release.

JOHN CYRIL HERBERT HURD.
